(57) **CLAIM**

The ornamental design for a “drinking container cap assembly,” as shown and described.

DESCRIPTION

FIG. 1 is a top, front, and right side perspective view showing my new design for a drinking container cap assembly and with a cap closure in a closed configuration.

FIG. 2 is a top view of the drinking container cap assembly shown in FIG. 1.

FIG. 3 is a right side view of the drinking container cap assembly shown in FIG. 1, the left side being substantially a mirror image thereof.

FIG. 4 is a front view of the drinking container cap assembly shown in FIG. 1.

FIG. 5 is a rear view of the drinking container cap assembly shown in FIG. 1.

FIG. 6 is a bottom view of the drinking container cap assembly shown in FIG. 1.

FIG. 7 is a top, rear, and left side perspective view of the drinking container cap assembly shown in FIG. 1, but with the cap closure in an opened configuration.

FIG. 8 is a top view of the drinking container cap assembly shown in FIG. 7.

FIG. 9 is a left side view of the drinking container cap assembly shown in FIG. 7.

FIG. 10 is a front view of the drinking container cap assembly shown in FIG. 7.

FIG. 11 is a rear view of the drinking container cap assembly shown in FIG. 7; and,

FIG. 12 is a bottom view of the drinking container cap assembly shown in FIG. 7.

The broken lines in the drawings depict environmental subject matter only and form no part of the claimed design.
